UNITED STATES PATENT OFFICE

2,218,887

VENTILATING PUTTYLESS SASH

Sern Madsen and Hilbert C. Mueller, Clinton,
Iowa, assignors to Curtis Companies Incorporated,
Clinton, Iowa, a corporation of Iowa

Application September 28, 1938, Serial No. 232,121

12 Claims. (Cl. 20—53)

An object of our present invention is to provide a simply and inexpensively constructed ventilating sash which does not require putty for mounting the glass panes therein, grooves being provided for the panes and the panes being slideable relative thereto for easy removal and replacement, the sash being constructed however so that ventilation can be secured by opening a section thereof, which when closed, provides a substantially weather tight sash.

Another object is to provide a sash which is very inexpensive, particularly by eliminating the necessity of putting the glass panes in position so that the sash may be economically used for farm building and other low cost housing installations.

Another object is to provide a sash having a stationary section and a removable ventilating section, both sections having grooves to receive the side edges of glass panes and the upper rails of both sections being relatively thin to permit passage of the glass panes thereby during the insertion or removal of the panes relative to the sections.

A further object is to provide a sash comprising rails and stiles in which the stiles are of uniform thickness throughout their height and to provide stationary and ventilating sections which have stiles of similar cross section, the stiles of the stationary section cooperating with the stiles of the sash to form therewith substantially unitary stiles and the stiles of the ventilating section being a continuation of the stiles of the stationary section whereby the window has a substantially uniform appearance throughout the height of the stiles and the glass panes used in both the stationary and ventilating sections are of uniform size.

Another object is to provide a rabbeted connection between the stiles of the ventilating section and the stiles of the sash frame to prevent easy entrance of water through the sash around the ventilating section, a similar rabbeted connection being provided between the sash frame stiles and those of the stationary section whereby uniformity in the cross section of the sash frame, stationary section and ventilating section stiles may be had throughout the height of the window sash.

Another object is to provide the top rail of the sash frame and the bottom rail of the ventilating section with rabbets and to provide a rib of each rabbet to lap outwardly and downwardly over the top edge of the ventilating section and stationary section respectively, such

ribs providing water shed connections and the rabbeted portions providing shoulders which normally prevent the removal of the glass panes from the ventilating and stationary sections.

Still a further object is to rabbet the lower rails of the ventilating and stationary sections along their upper outer edges, the rabbets being formed with downwardly and outwardly inclined surfaces on which the lower edges of the glass panes rest and which surfaces drain water away from the panes.

Still another object is to provide the ventilating section removable either bodily or partially by swinging it outwardly on a hinged connection whereupon the glass panes may be removed, the hinged arrangement and hardware for opening the ventilating section and retaining it in various open positions being so designed as to prevent removal of the glass panes except as disengagement of the hardware permits.

Still another object is to provide a ventilating puttyless sash to which screen wire can be applied very inexpensively, the hardware for opening the ventilating section being so designed that there is a minimum of interference between the screen and the hardware, the hardware necessitating the provision of only a small opening in the screen when applied to the sash through which a thrust bar of the hardware may slide.

With the foregoing and other objects in view our invention will be apparent from the following description in connection with the drawings. The invention is illustrated by the preferred embodiment thereof shown in the accompanying drawings in which:

Figure 1 is an inside elevation of a ventilating puttyless sash embodying our invention.

Figure 2 is an enlarged sectional view on the line 2—2 of Figure 1.

Figure 3 is an enlarged sectional view on the line 3—3 of Figure 1.

Figure 4 is an enlarged sectional view on the line 4—4 of Figure 1 showing by dotted lines the ventilating section of the sash in an adjusted open position and in a further open position which permits removal of the glass panes therefrom.

Figure 5 is an enlarged sectional view on the line 5—5 of Figure 1 showing the hardware at the center of the window.

Figure 6 is an enlarged sectional view on the line 6—6 of Figure 1 showing the withdrawal of the glass pane from the ventilating section of the sash; and

Figure 7 is a sectional view similar to the

right-hand portion of Figure 2 showing a turn button to retain the ventilating section in position when it is not hinged as in Figure 6.

On the accompanying drawings we have used 5 the reference characters 10 and 12 to indicate the stiles and top rail of a window sash frame. A fourth rail 13 completes the sash frame.

Within the sash frame a lower stationary section and an upper ventilating section are provided. The stationary section comprises the rail 13, a top rail 14, stiles 15 and a muntin 16. The ventilating section comprises bottom and top rails 17 and 18, stiles 19 and a muntin 20. The stationary and ventilating sections are completed 15 by glass panes 21 and 22 respectively.

The stiles 10 are of the same cross section throughout their height as shown in Figures 2 and 3. They are rabbeted as illustrated at 23 while the stiles 15 and 19 are reversely rabbeted 20 as at 24. The stiles 15 cooperate with the stiles 10 to form a unitary stile for the stationary sash section, the rabbets 23 and 24 in Figure 3 being shown assembled tightly together and retained in assembled position by tenons 25 of the rail 14 25 extending into mortises of the stiles 10. The lower ends of the stiles 10 and 15 are slotted to receive tenons 13a on the ends of the bottom rail 13. The rabbets 23 and 24 along the stiles 19 of the ventilating section are provided with clearance as shown in Figure 2 so that the ventilating section may be readily removed or swung outwardly in case the ventilating section is hinged as shown in Figure 4.

The stiles 15 and 19 and the muntins 16 and 20 35 are grooved as indicated at 26 to slidably receive the side edges of the panes 21 and 22. The ends of the muntins 16 and 20 may be provided with tenons 27 to fit in mortises 28 of the rails 13, 14, 17 and 18. The outer upper edges of the rails 13 40 and 17 are rabbeted so as to provide sloping shoulders 29 against which the lower edges of the panes 21 and 22 rest as illustrated in Figures 4 and 5. These shoulders support the glass panes and effectively shed water therefrom.

45 The lower edges of the rails 12 and 17 are rabbeted whereby ribs 30 are provided as shown in Figure 4. The ribs 30 lap over the upper edges of the stationary and ventilating sash sections and over the upper edges of the panes 21 and 22 50 to provide water sheds and thereby prevent water from running inside the panes. The rails 14 and 18, it will be noted, by reference to Figure 4 are of less thickness than the stiles 15 and 19 so that the panes 21 and 22 can be slid past them 55 when entering the grooves 26.

In Figure 4 I have shown hinges 31 on the outside of the window attached to the rails 12 and 18 for mounting the ventilating section of the sash. Hardware is provided in the form of a 60 bracket plate 32 and a thrust bar 33 together with a second bracket plate 34 and a hinge plate 35 for adjusting the degree of opening of the ventilating section relative to the sash frame. The bracket plate 32 has an opening 36 formed 65 therein through which the thrust bar 33 may be slid. A finger 37 extends upwardly from the bottom of the opening 36 for selective coaction with one of a plurality of spaced perforations 38 in the thrust bar 33. Such a position of adjustment is shown by dotted lines in Figure 2 and by dotted lines in Figure 4 wherein the ventilating section is only slightly opened.

70 The hinge plate 35 is pivoted on a pin 39 carried by ears 40 of the bracket plate 34. The ears 75 40 are located in a socket 41 formed in the lower

rail 17 of the ventilating sash section. The thrust bar 33 is pivoted to the hinge plate 35 by a rivet 42. The pivot pin 39 permits various degrees of inclination of the thrust bar 33 relative to the plane of the ventilating sash section as shown by dotted lines in Figure 4 while the rivet 42 permits movement of the thrust bar 33 from the dotted position of Figure 2 when the ventilating sash section is open to the full line position thereof when the ventilating section is closed. The edge of the thrust bar then engages the bracket plate 32 to retain the ventilating section in closed position. A hooked end 43 on the thrust bar 33 may be sprung into position behind the head of a screw 44 mounted in one of the stiles 15 to retain the thrust bar in its locked position substantially parallel to the plane of the window.

The upper ends of the grooves 26 for the panes 21 and 22 are open so that the panes can be slid upwardly for removal. In the closed position of the ventilating sash section however it is obvious that the panes cannot be removed. When the sash is swung to open position, the edges of the thrust bar 33 as shown by dotted lines in Figure 2 overlap the edges of the panes 21 so that they cannot be removed while the panes 22 cannot be removed because of the upper rail 12 of the sash frame. By swinging the ventilating section to the position of Figure 6, however, the panes 22 30 can be slid out for renewal purposes. This position is possible only by disengaging a portion of the hardware such as the bar 33 from the bracket plate 32 as shown by dotted lines in Figure 4. A notch 33a in the side of the bar 33 permits the bar to be raised out through a slot 32a in the top of the plate 32. The slot is narrower than the body of the bar.

In some instances it may not be desirable to provide the hinges 31, but merely have the ventilating section of the sash entirely removable. This can be accomplished by placing a plurality of turn buttons 45 on the rails and stiles 17, 18 and 19 as shown in Figure 7 to retain the ventilating section of the sash in position when the buttons are turned to the position shown. They may be rotated a quarter of a turn for permitting removal of the ventilating sash section. When the ventilating section is removed, of course, then the panes may be withdrawn from it and from the stationary section also.

The screening of our window structure is comparatively simple. The screen wire is shown at 46 in Figure 1 and consists of a rectangular piece which may be tacked or otherwise secured to the sash frame. To avoid confusion on the drawing only a portion of the screen is shown and the remaining outline of the screen is shown by dot and dash lines. Also a rectangular opening 47 in the screen is shown by dotted lines in this figure 55 and by solid lines in Figure 5. This opening 47 surrounds a portion of the bracket plate 32 so that the screen does not interfere with passage of the thrust bar 33 therethrough.

To facilitate replacement of the glass panes 21 65 and 22, the screen 46 should be readily removable. We have accordingly shown molding strips 48 to retain it in position and screws 49 for securing the molding strips to the sash frame.

From the foregoing description of our window 70 structure, it will be obvious that we have provided one in which the glass panes are assembled with a minimum of expense for material and labor. The grooves 26 receive the edges of the glass panes 21 and 22 so that they can be readily removed, 75

such removal, however, being impossible when the window is closed. The hardware and upper rail of the sash frame are so designed and associated with the structure that the panes of glass can be removed only by adjustment of the hardware and ventilating section to predetermined non-normal positions. The cross sectional shapes of the various parts are so designed that the sash throughout its area is substantially weather tight yet a ventilating section is provided which can be opened at will. The cross sectional shapes are retained throughout the various parts as much as possible (for instance the stiles 10, 15 and 19) so as to provide for uniformity in manufacture, variations in assembly making it possible to use the same stiles for the stationary section as for the ventilating section.

When the ventilating section is placed in the sash frame and is in closed position it is flush 20 with the opposite faces thereof and a succession of overlaps and glass panes provide a water shed from top to bottom of the assembled unit. Removal of the panes is had only by adjustment of the parts of the sash to a predetermined relationship and all panes of glass in the window may be of uniform size. The window, of course, may be built in several styles with different numbers and arrangements of glass panes and ventilating sections. Also our window is readily screened 30 without interference of the screen with the operating hardware.

While we have illustrated and described a preferred form of construction for carrying our invention into effect, the embodiment shown is capable of some modification without departing from the spirit and purpose of our invention. We, therefore, do not wish to be limited to the precise details of construction set forth but desire to avail ourselves of such variations, modifications 40 and use of mechanical equivalents as come within the scope of the appended claims.

Having thus described our invention what we claim and desire to protect by Letters Patent is:

1. In a ventilating puttyless sash, a sash frame 45 comprising an upper rail and stiles, a stationary sash section therein comprising rails and stiles, the bottom rail of said stationary section coacting with the bottom ends of said sash frame stiles to form therewith a complete sash frame, the stiles of said stationary section fixedly cooperating with the stiles of said sash frame, a ventilating sash section comprising rails and stiles, said last stiles being aligned with the stiles of said stationary section, the stiles of said stationary and ventilating sections having grooves to slidably receive the side edges of glass panes, glass panes received in said grooves, the bottom rails of said stationary and ventilating sections being engaged by the lower edges of said glass 60 panes whereby to support said panes, the upper rails of said stationary and ventilating sections being of less thickness than the stiles of said sections to permit passage of said panes alongside thereof when inserted or withdrawn relative to 65 said grooves, said ventilating section being removable relative to said sash frame to permit extraction of said panes upwardly from said grooves.

2. In a ventilating puttyless sash, a sash frame comprising an upper rail and stiles, a stationary 70 sash section therein comprising rails and stiles, the bottom rail of said stationary section coacting with the bottom ends of said sash frame stiles to form therewith a complete sash frame, the stiles of said stationary section fixedly co- 75 operating with the stiles of said sash frame, a

ventilating sash section comprising rails and stiles, said last stiles being aligned with the stiles of said stationary section, the stiles of said stationary and ventilating sections having grooves to slidably receive the side edges of glass panes, glass panes received in said grooves, the bottom rails of said stationary and ventilating sections being engaged by the lower edges of said glass panes whereby to support said panes, said ventilating section being hinged at its top to the sash frame and swingable to a position permitting extraction of said panes from said grooves. 10

3. In a ventilating puttyless sash, a sash frame containing a stationary sash section and a ventilating sash section, said frame and sections each 15 having stiles and rails, said sash frame and said stationary section having a common bottom rail, the stiles of said stationary and ventilating sections having grooves to slidably receive the side edges of glass panes, glass panes received in said 20 grooves, the bottom rails of said stationary and ventilating sections being engaged by the lower edges of said glass panes whereby to support said panes, said ventilating section being movable to an open position relative to said sash frame which 25 permits extraction of said panes upwardly from said grooves, said section, when closed, preventing such extraction.

4. In a ventilating sash, a sash frame comprising an upper rail and stiles, a stationary sash 30 section therein comprising rails and stiles, the bottom rail of said stationary section coacting with the bottom ends of said sash frame stiles to form therewith a complete sash frame including said top rail of said sash frame, the stiles of 35 said stationary section fixedly cooperating with the stiles of said sash frame, a ventilating sash section comprising rails and stiles, said last stiles being aligned with the stiles of said stationary section, the stiles of said stationary and ventilating section having rabbeted connection with the stiles of said sash frame and said ventilating section being hinged at its top to the sash frame 40 for outward swinging adjustment and having the rabbeted connection between its stiles lapping over the outside of the sash frame stiles. 45

5. In a ventilating sash, a sash frame comprising an upper rail and stiles, a stationary sash section therein comprising rails and stiles, the bottom rail of said stationary section coacting with the bottom ends of said sash frame stiles to form therewith a complete sash frame including said top rail of said sash frame, the stiles of said stationary section fixedly cooperating with the stiles of said sash frame, a ventilating sash section comprising rails and stiles, said last stiles being aligned with the stiles of said stationary section, the stiles of said stationary and ventilating sections having rabbeted connection with the stiles of said sash frame and the top rail of said sash frame and the bottom rail of said ventilating section having ribs lapping over the upper outer edges of said ventilating and stationary sections respectively. 55

6. In a ventilating sash, a sash frame, a lower stationary sash section and an upper ventilating sash section mounted therein, said frame and lower sash having a common bottom rail, the upper rail of said sash frame having a rib lapping over the outer upper edge of the ventilating sash section, the ventilating section having a rib lapping over the outer upper edge of the stationary sash section, said stationary and ventilating sash sections having stiles, said sash frame having stiles, said stationary and ventilating sash section 60

- stiles aligned with each other and said sash frame stiles being rabbeted similarly throughout their lengths to coat with said stationary and ventilating sash section stiles, means for securing 5 said stationary section stiles permanently to said sash frame stiles and means for hinging the ventilating section to the sash frame to permit opening of the ventilating sash section relative to the sash frame.
10. 7. In a ventilating puttyless sash, a sash frame, a stationary sash section and a ventilating sash section contained therein, said sash frame employing a bottom rail in common with said sash section, the stiles of said sections having grooves 15 to slidably receive the side edges of glass panes, glass panes received in said grooves, the bottom rails of said stationary and ventilating sections being engaged by the lower edges of said glass panes whereby to support said panes, said bottom rails having rabbets provided with inclined 20 horizontal faces to drain water from the lower edges of said panes.
8. In a ventilating sash, a sash frame comprising an upper rail and stiles, a stationary sash section therein comprising rails and stiles, the bottom rail of said stationary section coating with the bottom ends of said sash frame stiles to form therewith a complete sash frame, the stiles of said stationary section fixedly cooperating with the stiles of said sash frame, a ventilating sash section comprising rails and stiles, said last stiles being aligned with the stiles of said stationary section, glass panes in said sections, the bottom rails of said sections being engaged by the lower 25 edges of said glass panes whereby to support said panes, said bottom rails having rabbets provided with inclined horizontal faces to drain water from said panes and vertical faces to lap upwardly behind said panes.
30. 9. In a window structure of the character described, a sash frame having stationary means to receive glass panes, a removable ventilating section therein having means to receive other glass panes, said means having top rails of less thickness than the thickness of said means, said panes overlapping the outside faces of said top rails, said panes being parallel to the faces of said sash frame and being removable upwardly from pos- 35
- tion only when said removable ventilating section is removed from said sash frame and prevented from doing so when it is in closed position relative to said sash frame.
10. 10. In a window structure of the character described, a sash frame having stationary means to receive glass panes, a removable ventilating section therein above said glass panes and having means to receive other glass panes, said means having top rails, said panes overlapping the outside faces thereof, all of said panes being parallel to the faces of said sash frame and being removable upwardly from position when said removable sash section is removed from said sash frame and prevented from doing so by said removable section and by the top rail of said sash frame when said ventilating section is in closed position relative to said sash frame.
11. 11. In a window structure of the character described, a sash frame having stationary means to receive glass panes, a removable section therein having means to receive other glass panes, all of said panes being parallel to the faces of said sash frame and removable upwardly from position, said sash frame and removable section having respectively a top rail and a bottom rail which are rabbeted to lap over the upper edges of said glass panes and depend downwardly over the outside surfaces thereof, said means including narrowed top rails abutting against the inside surfaces of the top marginal edges of said panes.
12. 12. In a window structure of the character described, a sash frame having stationary means to receive glass panes, a movable section therein having means to receive other glass panes, all of said panes being parallel to the faces of said sash frame and removable from said stationary means and from said movable section, said sash frame and movable section having respectively a top rail and a bottom rail which are rabbeted to lap over the upper edges of said glass panes and depend downwardly over the outside surfaces of said panes, said means including top rails of less thickness than the thickness of said sash frame, the upper marginal edges of said panes abutting the outer faces thereof.
40. 45. SERN MADSEN.
HILBERT C. MUELLER.
